COMBINED TABLE AND MULTIPLE CHAIR UNIT FOR OUTDOOR USE

James E. Miller, Birmingham, Mich., assignor to Form,
Incorporated, Livingston, Mich.

Filed Jan. 16, 1973, Ser. No. 324,203

Term of patent 14 years

Int. Cl. D6—05

U.S. Cl. D6—45

FIG. 1

FIG. 3

FIG. 2

FIG. 4

FIG. 5

FIG. 6

FIG. 7

FIG. 8

FIG. 1 is a top, plan view showing my new design for a combined table and multiple chair unit for outdoor use.

FIG. 2 is a front elevational view thereof, the rear elevational view being a mirror image thereof.

FIG. 3 is a front elevational view, in perspective, of such new design, the corresponding rear view being a mirror image thereof.

FIG. 4 is a left, front perspective view of the design, the right rear view being a mirror image thereof.

FIG. 5 is a cross-sectional view taken on line 5—5 of FIG. 2.

FIG. 6 is a cross-sectional view taken on line 6—6 of FIG. 2.

FIG. 7 is a modified form of the article of FIG. 1 wherein four chairs are used and the base element is square rather than rectangular.

FIG. 8 is a left, front perspective view of the modification of FIG. 7, the right rear view being a mirror image thereof.

I claim:

The ornamental design for a combined table and multiple chair unit for outdoor use, as shown and described.
